UNITED STATES PATENT OFFICE.

HARRY C. GAMMETER, OF CLEVELAND HEIGHTS, OHIO.

DESIGN FOR A SIGN.

Application filed October 7, 1927. Serial No. 23,662. Term of patent 3½ years.

To all whom it may concern:

Be it known that I, HARRY C. GAMMETER, a citizen of the United States, residing at Cleveland Heights, in the county of Cuyahoga and State of Ohio, have invented a new, original, and ornamental Design for Sign, of which the following is a specification, reference being had to the accompanying drawing, forming part hereof, wherein the figure is a perspective view of a sign showing my new design.

I claim—

The ornamental design for a sign, as shown.

HARRY C. GAMMETER.
